[57] CLAIM

The ornamental design for a cupboard, as shown and described.

DESCRIPTION

FIG. 1 is a front elevational view of a cupboard showing my new design;

FIG. 2 is a right side elevational view thereof;

FIG. 3 is a top plan view thereof;

FIG. 4 is a bottom plan view thereof; and

FIG. 5 is a front and left side perspective view thereof. The rear surface is conventionally flat and unadorned.

FIG.3

FIG.2

FIG.1

FIG.4

FIG. 5
